US0D1111491S

(12) United States Design Patent (10) Patent No.: US D1,111,491 S
(45) Date of Patent: * Feb. 10, 2026

(54) BENCH

- (71) Applicant: Apple Inc., Cupertino, CA (US)
- (72) Inventors: Julien Phillip Stockwell, San Francisco, CA (US); Kully Kraig Mandon, Santa Cruz, CA (US); Po Huang, Campbell, CA (US); Peter Russell-Clarke, San Francisco, CA (US); Christopher M. Green, Woodside, CA (US); David Kahl Peschel, San Carlos, CA (US)
- (73) Assignee: Apple Inc., Cupertino, CA (US)
- () Term: 15 Years
- (21) Appl. No.: 29/922,637
- (22) Filed: Dec. 22, 2023
- (51) LOC (15) Cl. 06-01
- (52) U.S. Cl.
USPC D6/336; D6/381
- (58) Field of Classification Search
USPC D6/334-337, 349, 360, 361, 369,
D6/381-384, 641, 642, 644, 648
CPC A47C 17/00; A47C 17/02; A47C 17/04;
A47C 7/24; A47C 13/00; A47B 83/00
See application file for complete search history.

(57) CLAIM

The ornamental design for a bench as shown and described.

DESCRIPTION

FIG. 1 is a top front isometric view of the first embodiment of a bench, showing the claimed design;

FIG. 2 is a top rear isometric view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a top front isometric view of the second embodiment of a bench;

FIG. 9 is a top rear isometric view thereof;

FIG. 10 is a front elevation view thereof;

FIG. 11 is a rear elevation view thereof;

FIG. 12 is a left side elevation view thereof;

FIG. 13 is a right side elevation view thereof; and,

FIG. 14 is a top plan view thereof.

1 Claim, 14 Drawing Sheets
